UNITED STATES PATENT OFFICE.

EMILE DECAUVILLE, OF PARIS, FRANCE.

PRESS FOR TESTING THE BASES OF ARTILLERY-SHELLS AND THE LIKE.

1,250,101.

Specification of Letters Patent.

Patented Dec. 11, 1917.

Application filed October 21, 1916. Serial No. 126,925.

To all whom it may concern:

Be it known that I, EMILE DECAUVILLE, of 248 Rue Lecourbe, Paris, in the Republic of France, engineer, have invented Presses for 5 Testing the Bases of Artillery-Shells and the like, of which the following is a full, clear, and exact description.

For testing the pressure capable of being supported by the bases of shells, various apparatuses have been invented to press the base 10 of the shell against the bed of the press; in some the pressure is exerted upon the edge of the eye or opening in the point of the shell, and there is frequently produced a deformation 15 of the adjacent part which is screw-threaded to receive the fuse; in other systems of presses the pressure is transmitted to the body of the shell by means of a ring, which arrangement is not practical 20 when the shell has a very elongated form, for under the pressure exerted there is produced a wedging of the shell in the interior of the ring, or there appear after the pressure faults or irregularities of manufacture.

25 The present invention has for its object to produce a press which will avoid these inconveniences.

This press is characterized essentially by the fact that the pressure of the shell against 30 the bed of the press is exercised through the medium of a liquid.

The improved press comprises in principle:

(a) A fixed press body into which is introduced 35 partially the shell so that this latter may move, in the manner of a piston or ram, in the interior of the press body under the action of the liquid forced into this latter:

40 (b) A movable or removable bed or abutment to permit the introduction of the shell into the body of the press and to allow it to be withdrawn before or after the testing; this bed may, for example, be mounted upon 45 the body of the press by a bayonet fastening, or be hinged upon the body of the press, or be capable of receiving a lateral or transverse motion.

The liquid is forced into the body of the 50 press by a piston or ram moved by means of a screw, or by means of a pump, or by an accumulator combined with a step-up contrivance, or by any other appropriate means.

In order to obtain a rapid filling of the 55 press body before the introduction of the shell, and to prevent any air remaining be-

tween the pressure fluid and the shell at the moment of testing, the body of the press is preferably connected to a filling tank containing water in such a manner that this 60 water fills the body of the press upon the principle of communicating vessels, and, at the moment when the shell is introduced, a part of this water, driven by the shell, returns to the tank; a needle valve enables 65 communication to be made between the tank and the body of the press when pressure should be exerted in this latter.

The accompanying drawings illustrate by way of example various methods of carrying 70 the invention into effect.

In these drawings,

Figures 1 and 2 are a vertical section and a sectional side elevation respectively of a method of carrying the invention into practice.

Figs. 3 and 4 are a vertical section and a sectional plan view respectively of a modification.

Figs. 5 and 6 are a vertical section and a 80 sectional side elevation of another method of carrying the invention into effect.

In one method of carrying the invention into effect the press comprises a press body *a* having at its upper part a circular opening provided with a cup leather *b* and into which is introduced the shell *c* to be tested, the eye or opening in its end being preferably closed by a plug provided with a tight joint; this shell is introduced in such a manner that its point enters the body *a* of the press and its cylindrical part is in contact with the cup leather *b*.

The press body *a* has at its lower part a cylindrical cavity *d* which is in communication at one part with the cavity provided to receive the shell, and at another part with a filling tank *e* containing water to be used for filling the press body *a* before the introduction of the shell; a suitable valve *f* enables communication to be made or broken between the tank *e* and the press body.

In the interior of the lower cylindrical cavity *d* moves a ram *g* which exercises the desired pressure upon the liquid contained 105 in the body of the press; this ram is moved by means of a screw *h* passing through a fixed nut *i* carried by arms *j* fixed with respect to the press body; this screw *h* carries at its end a fly or fly wheel *k* by which it is 110 rotated.

Upon the press body *a* is mounted by

means of a bayonet catch, the bed *l* or abutment, which has a projection *m* against which is applied the base of the shell.

To enable the bed *l* to be readily moved 5 this latter is provided with a counter-balance weight *n*.

The operation of this press is as follows:

The bed *l* having been disengaged from 10 the press body *a* and raised above this latter, the valve *f* is opened to admit water from the filling tank *e* into the press body; when this latter is full of water the shell is placed in position in the press body, the point of the shell being downward; due to its weight 15 the shell descends in the press body, driving back a part of the water into the filling tank *e*; the valve *f* is then closed so as to interrupt communication between the press body *a* and the tank *e*; then the fly or fly wheel *k* 20 is rotated to press the ram *g* into the interior of the lower cylindrical cavity *d*; the water contained in the press body below the shell transmits to this latter the pressure exerted by the ram *g*; under the action of this 25 pressure the shell is caused to rise and its base is thus applied against the projection *m* carried by the bed or abutment *l*.

It will be noticed that the pressure transmitted is uniformly spread over the whole 30 surface of that part of the shell which enters the press body, and that during the testing the reaction is supported by the press body.

When the testing is finished the fly *k* is 35 rotated in the reverse direction so as to withdraw the ram *g* and cause the pressure below the shell to cease; then the bed or abutment *l* of the press body is disengaged and raised so that the shell may be removed from the 40 press body.

In the modification illustrated in Figs. 3 and 4 the pressure is transmitted to the water which fills the cavity of the press body and which has been furnished by a 45 filling tank *e* as above described, by a pressure pump which forces water under pressure into the press body by means of a tube *o* which communicates with a channel *p* formed in the press body *a* and opening into 50 the cavity of this latter.

In this modification the bed or abutment *l* is capable of being displaced by an oscillating movement; the press body *a* has two trunnions *a*¹ upon which are hinged the two 55 cheeks of the bed *l*, and it also has two stops *q* *q*¹ between which moves a heel *r* carried by one of these cheeks.

In another modification illustrated in 60 Figs. 5 and 6 the pressure is transmitted to the water in the press body by a step-up arrangement. The press body *a* is prolonged at its lower part by an auxiliary pump body *d*¹ in which moves a pressure piston *g*¹.

At the upper part of this auxiliary pump

body *d*¹ is formed a channel *f*¹ for the introduction of the filling water, and it is connected to a tank as previously stated or to any water pipe under pressure; a valve *f* allows communication to be made or broken 70 between the press body and the filling pipe.

At the lower part of the body *d*¹ of the auxiliary pump, in the part situated below the pressure piston *g*¹, there is formed a channel *p* for the admission of water under 75 high pressure furnished by an accumulator or other convenient apparatus; a suitable valve *s* allows the water at high pressure to be admitted or to be cut off.

The pump body *d*¹ has an opening *t* intermediate of its ends upon which is branched a pipe *u* to allow the escape of any water which has leaked past the piston.

The combined press body *a* and body *d*¹ of the auxiliary pump are mounted upon a 85 frame *v*.

In this modification the displacement of the bed or abutment *l* is effected by a transverse movement. The bed is mounted upon four small rollers or wheels *w* which rest 90 upon rails *x*, which latter are carried by the said frame *v*; the two cheeks of this bed have each, upon their inner face, a projecting part *t*¹ which may come into contact with a shoulder *y* upon the press body. 95

The operation of these two modifications is the same in principle as that of the first described construction illustrated in Figs. 1 and 2.

It will be understood that these constructions above described are only given as examples and that the form, dimensions and details of construction may be modified.

Claims.

1. A press for testing the bases of artillery shells and the like, comprising a press body into which the shell is partially introduced so that the latter may move therein in the manner of a ram,—means for sending a liquid under pressure in the interior of the said press body, so as to tend to move the shell,—and a bed against which the base of the shell is driven under the action of the water forced into the press body. 105

2. A press for testing the bases of artillery shells and the like, comprising a press body into which the shell is partially introduced so that the latter may move therein in the manner of a ram,—means for sending a liquid under pressure in the interior of the said press body, so as to tend to move the shell,—and a bed against which the base of the shell is driven under the action of the water forced into the press body, the said bed being movable to permit the introduction of the shell in the press body before the testing and its withdrawal after the testing. 115

3. A press for testing the bases of artillery shells and the like, comprising a press 125

body into which the shell is partially introduced so that the latter may move therein in the manner of a ram,—a filling tank containing water, in communication with the 5 press body,—means for interrupting the communication between the said filling tank and the press body,—means for exerting the required pressure upon the water filling the interval between the press body and the 10 shell,—and a bed against which the base of the shell is driven under the action of the water forced into the press body, the said bed being movable to permit the introduction of the shell in the press body before the 15 testing and its withdrawal after the testing.

4. A press for testing the bases of artillery shells and the like, comprising a press body having at its upper part a circular opening provided with a leather cup and 20 into which the shell is partially introduced so that the latter may move therein in the manner of a ram, the eye of this shell being previously closed by a plug,—there being a cylindrical cavity provided in the press body

and communicating with the cavity of the 25 latter adapted to receive the shell,—a filling tank in communication with the said cylindrical cavity,—means for interrupting the communication between this filling tank and the cylindrical cavity,—a ram movable in the cylindrical cavity and adapted to exert the required pressure upon the liquid contained in the press body,—means for actuating this ram,—and a bed against which is 30 driven the base of the shell under the action of the water forced in the press body, the said bed being removably mounted on the press body to permit the introduction of the shell into the press body before the testing and its withdrawal after the testing. 35

The foregoing specification of my press for testing the bases of artillery shells and the like, signed by me this twenty ninth day of September 1916.

EMILE DECAUVILLE.
